CIGARETTE LIGHTER

Alfred F. Fukal, Houston, Tex., assignor, by mesne assignments, to American Lighter Corporation, Fort Worth, Tex., a corporation of Texas

Filed May 18, 1964, Ser. No. 80,034

Term of patent 14 years

(Cl. D48—27)

FIG. 1

FIGURE 2 is a top plan view of the device shown in FIGURE 1; the bottom view is similar in outline to the top view but is plain;

I claim:

The ornamental design for a cigarette lighter, as shown and described.
